UNITED STATES PATENT OFFICE.

HARRY C. HUBBELL, OF JERSEY CITY, NEW JERSEY.

CATHODE-PLATE FOR BATTERIES.

SPECIFICATION forming part of Letters Patent No. 793,078, dated June 27, 1905.

Application filed October 3, 1904. Serial No. 227,067.

To all whom it may concern:

Be it known that I, HARRY C. HUBBELL, a citizen of the United States, residing at Jersey City, in the county of Hudson and State of New Jersey, have invented new and useful Improvements in Cathode-Plates for Batteries, of which the following is a specification.

This invention relates to cathode-plates for galvanic batteries and which serves only as a conductor for the current.

The principal objects of my invention are to provide a battery-plate for permanency and durability of low resistance and high conductivity and which will not separate and disintegrate under electrolytic action nor the active material be washed away by the agitation of the electrolyte. These and other objects are attained by means of the construction illustrated in the accompanying drawings, in which—

Figure 1 is a perspective view illustrating the different parts of the cathode-plate separated to show the general arrangement of layers. Fig. 2 is a plan view of the perforated foundation-plate. Fig. 3 is a plan view of the cathode-plate removed from its covering or pocket. Fig. 4 is a transverse section of the cathode incased in a wire-gauze pocket or cover.

Referring to the drawings for a more particular description of my invention, the numeral 1 denotes the foundation-plate of my cathode, said plate being formed of nickel or nickel-plated iron and provided with perforations 2 of the required size. In lieu of this foraminous foundation-plate I could use an open-wire work foundation; but the perforated sheet-metal plate has been found preferable. Deposited upon the perforated foundation-plate is a mass of finely-divided silver 3, the silver extending through the perforations 2 to firmly hold the silver to the foundation-plate. In order that the active material may be rendered more permanent and durable and to prevent disintegration or washing away by the action of the electrolyte, a layer of asbestos paper 4 or a sheet of similar mate-

rial not injuriously affected by the electrolyte is folded upon the plate to serve as a non-destructible protector and filter for the electrolyte. This layer of asbestos material may be in the form of a strip bent upon itself centrally, and thus adapted to cover both sides of the cathode-plate. A strip of fine wire-gauze, which should either be of nickel or nickel-plated iron, is folded in a like manner to the asbestos layer, and the pocket or foraminous casing thus provided serves to inclose and protect the plate and to give great durability to the same, the wire-cloth also serving to keep the pulpy asbestos paper in the proper position.

It will be noticed that the silver mass deposited upon the foundation-plate is beveled at its edges and bottom, as at 5, and that the outer edges and bottom edge of the foundation-plate are not covered with the deposit, thus providing smooth thin edges 6 for the attachment of binding-strips. The gauze pocket 7 is brought together at the sides and bottom to inclose the plate and asbestos layer, and the channeled binding-strips 8 are secured in place to firmly inclose and hold the parts together. The binding-strips 8 may be of nickel or nickel-plated iron or soft steel, and in order to hold the parts firmly together their upper ends may be crimped or pinched down, as at 9.

A cathode-plate made in accordance with this invention is permanent and durable, will not separate or disintegrate, and owing to the layer of asbestos paper and gauze pocket will be fully protected, while the electrolyte will filter through the fine meshes of the pocket and the paper without displacing or injuring the parts which go to make up the cathode as a whole.

Having thus fully described my invention, what I desire to secure by Letters Patent and claim is—

1. A cathode comprising a foraminous foundation, a silver-oxid mass deposited upon the opposite sides thereof and keyed through the perforations therein, a sheet of asbestos filtering material inclosing the plate, and a wire-

gauze pocket having binding-strips at its edges for inclosing the parts.

2. A battery-plate comprising a foraminous nickel foundation, a silver-oxid deposit upon its opposite sides, the edges of the foundation being uncovered by the deposit, a layer of asbestos paper surrounding the deposit, a

wire-gauze pocket inclosing the parts and held in place by channeled binding-strips crimped upon the edges of the gauze pocket. 10

HARRY C. HUBBELL.
